UNITED STATES PATENT OFFICE.

WILLIAM H. WEEKS, OF PHILADELPHIA, PENNSYLVANIA.

MACHINE FOR COATING CONFECTIONERY.

SPECIFICATION forming part of Letters Patent No. 634,633, dated October 10, 1899.

Application filed July 3, 1899. Serial No. 722,680. (No model.)

To all whom it may concern:

Be it known that I, WILLIAM H. WEEKS, a citizen of the United States, residing in the city and county of Philadelphia and State of Pennsylvania, have invented certain new and useful Improvements in Machines for Coating Confectionery, of which the following is a full, clear, and exact description, reference being had to the accompanying drawings, forming a part of this specification.

This invention relates to certain improvements in that class of machines whereby confections, such as cream-drops, are coated with liquid chocolate or other material, my improvements, as generally stated, comprising a novel construction of receptacle in which the coating material is maintained at the proper degree of consistency, means for agitating the liquid contents of said receptacle, means for supporting and operating the dipping-tray and the guard-screen therefor relatively to each other and to the receptacle, and means for supporting and jarring said tray for the purpose of removing superfluous coating from the contents of the tray, together with various novel features of construction and organization of parts that will be hereinafter particularly described and claimed.

In the drawings, Figure 1 is a side elevation of the machine. Fig. 2 is a plan thereof. Fig. 2^a is a detail of clutch. Fig. 3 is a vertical section, as on the line 3 3 of Fig. 1. Fig. 4 is a section on the line 4 4 of Fig. 3. Fig. 5 is a detail of dipping-tray.

35 A A are two uprights or end frames upon which is supported a vessel B, preferably semicircular, or substantially so, in cross-section, provided with a jacket b, to which steam and hot water are introduced by laterally-40 perforated pipes b', whereby the liquid contents (such as chocolate) of the vessel may be maintained at a proper degree of consistency. Extending from the forward side of the vessel and leading thereto is an inclined a 45 drip-pan B', which constitutes, in effect, a continuation of said vessel, being similarly provided with a steam-and-water jacket b'', which communicates with that of the vessel.

Suspended from bearings c at the respective ends of the vessel is a rock-frame C, which is adapted to swing within the vessel, and thereby agitate and intimately mix the con-

tents thereof. This frame comprises radial end bars c', connected at their lower extremities by longitudinal rails c² and end segments c³. The rails are preferably provided on their upper edges with studs or projections c⁴, which serve still more effectually to agitate and mix the composition. One end of the frame is connected by means of a rod or pitman c⁵ with an eccentric c⁶ on the main driving-shaft D, whereby the requisite oscillations of the frame are effected.

Fitted to uprights e on the ends of the vessel is a vertically-reciprocating cross-head E, which is connected by means of rods e' with sprocket-wheels e² on the respective ends of a shaft e³, that is journaled directly beneath the vessel in bearings in the end frames. These wheels are connected by sprocket-chains e⁵ with wheels e⁶ on a counter-shaft e⁷, and the latter shaft in turn is geared with the main shaft and adapted to be driven thereby at predetermined intervals. In the present instance a sprocket-wheel e⁸ is loosely mounted on the counter-shaft and connected by means of a chain e⁹ with a similar wheel e¹⁰, fast on the main shaft. The shaft e⁷ is provided with a clutch member e¹¹, which may be moved into and out of engagement with a corresponding member on the hub of the wheel e⁸, so as to render the latter fast or loose on its shaft, as desired. Normally the clutch member e¹¹ is held in engagement with that on the sprocket-wheel e⁸ by means of a suitably-disposed spring e¹². Connected with this spring-controlled clutch member is one arm of a lever e¹³, which is fulcrumed on an adjacent bracket e¹⁴, the other arm of the lever being connected by means of a link e¹⁵ with a bell-crank lever e¹⁶ on said bracket. Depending from the crank-lever is a rod e¹⁸, the lower end of which lies adjacent to the inner face of one of the sprocket-wheels e², which face is provided with a suitably-disposed lug or projection e¹⁹, that is designed in each turn of the wheel to abut against the lower end of the rod and raise the same, thus disengaging the clutch from the sprocket-wheel. The clutch will remain thus disengaged until the rod is freed from the lug or projection by the attendant. A forwardly-extending hand-bar e²⁰, connected with the rod, affords a convenient means whereby the

rod may be readily disengaged from the said lug or projection. It will be observed that the shafts D and e^7 have their bearings in parallel cross-bars e^8 , supported by the uprights e , above referred to.

On each end of the cross-head E are depending rods F, which are connected at their lower ends by a cross-bar f , from which in turn depends a series of parallel rods f' , having their lower or free ends turned inward to constitute hooks. During the reciprocation of the cross-head these hooks are lowered into and lifted from the interior of the vessel.

F' is a rectangular tray adapted to be detachably supported upon the hooked ends of the rods, and thereby lowered into and raised from the vessel. This tray is provided with open wire compartments f^x , in which are deposited the creams or other substance to be coated with the liquid contents of the vessel.

G is a screen which is arranged above the tray and is movable upon and from the latter during the operation of the machine, the function of the screen being to prevent displacement of the creams, &c., in the tray when the tray is dipped into the composition in the vessel. This screen is carried by the lower ends of vertical rods g , that are guided loosely in the cross-head. The upper ends of these rods are connected by links g' with the inner arms of trip-levers g^2 , that are fulcrumed at the respective ends of the cross-head. In the path of the outer arms of the levers are rollers g^3 , which are so disposed that in the upward stroke of the cross-head the said arms will abut against them, and thus raise the screen from the underlying frame, whereas in the downstroke of the cross-head the rollers will prevent the independent dropping by gravity of the screen upon the tray. These rollers g^3 are journaled in depending brackets e^{xx} , affixed to the cross-bars e^8 . At or about the end of each upward stroke of the cross-head the lug or projection e^{19} on the sprocket-wheel e^2 abuts against the opposing end of the clutch-controlling rod e^{18} and effects thereby the inaction of the counter-shaft, thus arresting the operation of the cross-head. The tray, with its coated contents, is then moved by the attendant onto an adjacent jarring-frame H, which is disposed directly above the drip-pan B', above referred to. This frame comprises horizontal guides h , (such as angle-irons,) supported upon parallel bars h' on the upper ends of vertically - reciprocative rods h^2 . These rods are fitted to guide-brackets h^3 on the side frames and maintained yieldingly elevated by spiral springs h^4 , which, encircling the rods, bear upon the said brackets and against collars h^5 on the rods, respectively. On the lower extremities of these rods are shoes h^6 , below which are disposed toothed wheels h^7 on a shaft h^8 . On one end of this shaft is a small pulley h^9 , which is belted with a larger pulley h^{10} on the main shaft and adapted to be driven thereby at a high rate of speed. It will thus be seen that if the rods be de-

pressed against the action of their springs into engagement with the teeth of the rapidly-revolving toothed wheels said rods and their connections will be rapidly vibrated. The weight of the tray, with its contents, is sufficient to overcome the pressure of the springs, and hence when it is moved onto the guides h the rapid jarring to which it is subjected shakes from the frame and its contents all the superfluous coating clinging thereto. The excess of coating drops into the underlying drip-pan and runs into the main receptacle. It will be seen that by the application of more or less additional weight upon the tray a corresponding increase in the jarring action will result.

On the bars h' , forwardly of the guides h , are corresponding guides h^{11} , onto which the tray, with its contents, is shifted by hand when the jarring operation has been completed, said latter guides being provided with inwardly-extending lips h^{12} , which take against the upper edges of the tray and maintain it in place. The guides h^{11} are centrally pivoted, as at h^{13} , so that they and the tray may be bodily turned or inverted. Preparatory to the removal of the contents of the tray a sheet of waxed paper or the like is laid upon the latter and a pan imposed thereon. The tray and pan are then inverted, thus depositing in the pan the contents of the tray. The guides h^{11} are then returned to their original position and the tray removed therefrom for a subsequent operation.

I preferably arrange directly above the screen a coil of pipe g^4 , through which steam and hot water are circulated for the purpose of keeping the screen hot, and thus preventing the hardening of the chocolate, &c., on the latter. This pipe is supported by suitable brackets g^5 , rising from the end frames of the machine. I also preferably impose upon or over this pipe a sheet of asbestos g^6 , so as to direct the heat down upon the screen.

The operation of the machine is as follows: The vessel B is supplied with chocolate and the same maintained in proper condition through the agency of the steam and water coursing through the pipes b' . Assuming the cross-head E with its depending tray-supporting rods to be elevated above the vessel and the spring-controlled clutch member e^{11} to be held disengaged from the corresponding member on the hub of the wheel e^8 through the action on the rod e^{18} of the lug or projection e^{19} on the proximate sprocket-wheel e^2 , power is applied to the main driving-shaft and transmitted therfrom to the shaft h^8 , carrying the toothed wheels h^7 , thereby rapidly revolving the latter. There being no load or tray upon the jarring-frame H the latter is maintained yieldingly elevated and out of engagement with the wheels h^7 . The screen is held some distance above the lower or hooked ends of the tray-supporting rods through the engagement with the opposing rollers g^3 of the trip-levers g^2 , that are linked with the vertical

rods g , by which said screen is suspended, and the rock-frame is swung to and fro within the vessel through the eccentric and rod connection with the main shaft, so as to agitate the liquid contents of the vessel. A tray, such as F' , provided with the creams or other substance to be coated is set by an attendant upon the elevated tray-supporting rods. Another attendant then operates the hand-bar e^20 , so as to disengage the rod e^{18} from the lug or projection e^{19} on the sprocket-wheel e^2 , thereby permitting the clutch member e^{11} to resume its normal position in engagement with that on the hub of wheel e^8 , and thereby lock the latter to its shaft e^7 , whereby this shaft is driven by the sprocket-gearing from the main shaft. In consequence the shaft e^3 below the vessel is driven through the sprocket-gearing e^2 , e^5 , and e^6 , and the cross-head is lowered through its connection by the rods e' with the wheels e^2 . The filled tray upon the tray-supporting rods on said head is thus lowered into the contents of the vessel and coated thereby. As the rotation of the shaft e^3 continues the cross-head and therewith the tray, with its coated contents, are raised above the vessel. As the cross-head reaches its uppermost position the lug e^{19} on the sprocket-wheel e^2 abuts against the opposing end of the rod e^{18} and raises the same, thereby effecting the release of the clutch device on the counter-shaft and rendering the latter quiescent, as above described. During the ascent of the cross-head the outer arms of the trip-levers g^2 abut against the opposing rollers g^3 , thereby lifting the rods g , and perforce raising the screen from the tray. An attendant then shifts the tray, with its coated contents, onto the horizontal guides h of the jarring-frame H , whereupon the latter is depressed against the compression of the springs h^4 and the shoes h^6 of said frame moved into engagement with the teeth of the rapidly-revolving wheels h^7 , thereby, as above explained, jarring the frame and tray and shaking therefrom the superfluous coating, the excess dropping into the drip-pan and running into the main receptacle. The tray, with its contents, is then shifted onto the pivoted guides h^{11} and the coated contents deposited in a pan and the tray removed for a subsequent operation, as above explained.

I claim—

1. In a coating-machine, the combination, with the liquid-containing receptacle, provided with an inclined drip-pan leading thereto, of a dipping-tray support, means for lowering it into and raising it from said receptacle, a tray-support arranged over the said drip-pan, and means for jarring said latter support.

2. In a coating-machine, the combination, with the liquid-containing receptacle provided with an inclined drip-pan leading thereto, of a reciprocating cross-head, a series of rods depending at intervals from said cross-head and having at their lower ends inwardly

turned lugs to support a dipping-tray, means for reciprocating said cross-head, a yielding tray-supporting frame arranged over said drip-pan, and jarring devices with which said frame is operatively engaged by a weight or load on the frame. 70

3. In a coating-machine, the combination, with the liquid-containing receptacle, provided with an inclined drip-pan leading thereto, of a reciprocating cross-head, a series of depending hooks connected therewith and adapted to support a dipping-tray, means for reciprocating said cross-head, a tray-support arranged over said drip-pan, and means for 80 jarring said latter support.

4. In a coating-machine, the combination, with the liquid-containing receptacle, provided with an inclined drip-pan leading thereto, of a dipping-tray support, means for lowering it into and raising it from the said receptacle, a tray-support arranged over said drip-pan, and means for jarring said latter support, together with a screen, and means whereby the same is applied to and removed from 90 said tray at predetermined intervals.

5. In a coating-machine, the combination, with the liquid-containing receptacle, semi-circular or substantially so, in cross-section, with an inclined drip-pan leading thereto, of 95 a rock-frame adapted to swing within said receptacle, and agitate the contents thereof, means for supporting said frame, and means for actuating the same, a dipping-tray support, means for lowering it into and raising 100 it from said receptacle, a tray-support arranged over the drip-pan, and means for jarring said latter support.

6. In a coating-machine, the combination, with the liquid-containing receptacle, semi-circular or substantially so, in cross-section, with an inclined drip-pan leading thereto, of a rock-frame adapted to swing within said receptacle and comprising radial end bars connected at their lower ends by longitudinal rails 110 provided with studs or projections, means for supporting said frame, and means for oscillating the same, a dipping-tray support, means for lowering it into and raising it from said receptacle, a tray-support arranged over the 115 drip-pan, and means for jarring said latter support.

7. In a coating-machine, the combination with a yielding supporting-frame for the tray, of jarring devices with which said frame is 120 operatively engaged by a weight or load on the frame.

8. In a coating-machine, the combination with a tray-supporting frame, including side guides, vertical rods, and springs, of toothed 125 wheels adjacent to said rods, and means for supporting and driving said wheels, whereby when a weight or load is applied to said frame the vertical rods thereof will be moved into operative engagement with said wheels. 130

9. In a coating-machine, the combination with a receptacle in which the coating sub-

stance is contained, and means for dipping a tray into and raising it from the said receptacle, of a yielding frame adjacent to said receptacle, and jarring devices with which said frame is operatively engaged by a weight or load on the frame.

10. In a coating-machine, the combination with the receptacle in which the coating substance is contained, of a driving-shaft, a counter-shaft, gearing for said shafts, a clutch whereby said gearing may be made fast or loose on one of said shafts, a reciprocating cross-head provided with means for supporting a dipping-tray, a wheel, a shaft therefor, a connection between said wheel and the cross-head, and means whereby the said clutch is actuated at predetermined intervals during the rotation of said wheel.

11. In a coating-machine, the combination with the receptacle for the coating composition, of a jarring-frame adjacent thereto, provided with pivoted supports for the tray.

12. In a coating-machine, the combination with the receptacle for the coating composition, of a yielding frame adjacent thereto, provided with pivoted supports for the tray, and jarring devices with which said frame is

operatively engaged by a weight or load on the frame.

13. In a coating-machine, the combination with the liquid-containing tank, the dipping-tray support, means for lowering it into and raising it from said receptacle, the screen arranged above said support, and means whereby said screen is applied to and removed from the tray at predetermined intervals, of heating-pipes supported above said screen.

14. In a coating-machine, the combination with the liquid-containing tank, the dipping-tray support, means for lowering it into and raising it from said receptacle, the screen arranged above said support, and means whereby said screen is applied to and removed from the tray at predetermined intervals, of heating-pipes supported above said screen, and a sheet of asbestos, or the like, imposed on said pipes.

In testimony whereof I have hereunto affixed my signature this 27th day of June, A. D. 1899.

WILLIAM H. WEEKS.
